UNIVERSAL CABLE-CLAMPING DEVICE

Leo L. Verkuil, Tottenville, Staten Island, N. Y., assignor to Edwards and Company, Inc., Norwalk, Conn., a corporation of New York

Application July 26, 1946, Serial No. 686,481

15 Claims. (Cl. 41—81)

1

This invention relates to flexible cable-clamping devices and more particularly to a device for attaching a flexible insulated conductor cable such as is employed in hospital signalling systems where the patient is provided with a signalling switch.

One of the objects of this invention is to provide a compact and efficient device for catching a signalling cable to the bed clothes such as a sheet, blanket or the like or to attach it to some other parts such as a bed post, rail or the like. Another object is to provide such a device that will be of dependable action and capable of avoiding damage to the part or parts to which the cable is to be attached and capable also of safeguarding the cable itself against material damage. Another object is to provide a device of the above mentioned character which can be embodied in relatively diminutive and also attractive form and which will be easy and simple to operate. Another object is to provide a cable-clamping device that will be of wide range of flexibility or adaptation to meet the widely varying conditions of practical use. Another object is to provide a device of the above mentioned character in which the individual parts are constructed so as to facilitate manufacture thereof individually and to facilitate assembly thereof into the completed device. Another object is in general to provide an improved clamping device, and other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawing in which are shown illustratively several of the various possible embodiments of this invention,

Figure 1 is a plan view or top elevation of the complete device;

Figure 2 is a front elevation;

Figure 3 is a bottom plan view as seen from the bottom of Figure 2;

Figure 4 is an end elevation as seen from the right in Figure 1 or Figure 2, certain parts being broken away to show more clearly certain internal parts;

Figure 5 is an exploded perspective view of several mounting and assembly parts;

Figure 6 is a detailed perspective view of one of the clamping units;

2

Figure 7 is an end elevation of a button or finger grip construction;

Figure 8 is a horizontal sectional view as seen along the line 8—8 of Figure 4;

Figure 9 is a diagrammatic view showing one possible method of cable-securing use of the device;

Figure 10 is a diagrammatic view illustrating another mode of coaction of the device with the cable;

Figure 11 is a front elevation of another embodiment of a complete device, showing certain alternative features of construction, and

Figure 12 is an end elevation as seen from the right in Figure 11, certain parts being broken away to show more clearly certain internal parts and the modified or alternative features above mentioned.

Similar reference characters refer to similar parts throughout the several views of the drawing.

The device comprises a housing 12 which is preferably made up to provide a top wall 13 from which depend opposed side walls 14, 15, and opposed end walls 16, 17; in the opposed end walls, 16, 17, are passages 18, 19, preferably in the form of slots which open into the lower edges of the end walls, being of a size to readily accommodate therein the flexible cable which may carry a number of insulated conductors and which is sometimes called a "flexible cord" or "flexible cable." Conveniently the walls of the slots 18 and 19 can be rounded as indicated in Fig. 4, the slots 18 and 19 being aligned so that a portion or reach of the cable, when inserted into the slots, bridges lengthwise across the interior space within the housing 12. The opposed side walls 14 and 15 are provided with passages 20 and 21, preferably aligned transversely of the housing and preferably in the form of slots which open into the lower edges of the side walls 14 and 15. They are to accommodate and expose therethrough manual actuators or finger pieces 22 and 23, respectively, which may be given any suitable shape that is convenient to the grip of the fingers of the hand so that the two actuators (see Figs. 1 and 4) may be simultaneously pressed inwardly of the slots 20 and 21 to actuate certain parts as is later described. Illustratively the actuators 22 and 23 may be given a shape which is substantially square or rectangular in cross section and hence the slots 20 and 21 (Fig. 2) may be substantially similarly shaped.

As appears better in Fig. 4, the device is pro-

vided with two opposed clamping jaws 26 and 27 which project downwardly from the interior of the housing 12 and below the aligned edges of its walls and hence project downwardly well beyond the region occupied by a cable that is seated in the slots 18 and 19. Coacting with the clamping jaws 26 and 27 and positioned internally thereof are two clamping elements 28 and 29, being preferably of any suitable springy sheet metal. Clamping jaws 26 and 27 are preferably made of relatively unyielding sheet metal and the spring or yielding clamping elements 28 and 29 are preferably mounted directly upon and carried by the plate-like clamping jaws 26 and 27 respectively.

Preferably jaw 26 and element 28 and certain related parts are made up as a single unit or sub-assembly so constructed and shaped that two such sub-assemblies can be used and assembled to provide the two pairs of clamping jaws or elements above described, thus to lessen the number of differently shaped parts, and tools therefor. In Fig. 6 one of these sub-assemblies is shown in perspective and let it be assumed that it represents the left-hand sub-assembly of Fig. 4 that includes the clamping jaw 26 and the clamping element 28; accordingly the clamping jaw 26 comprises a plate-like area of the sheet metal stock curved or bent along one end, where it may be serrated as at 30 for better gripping action as a clamping jaw, and at its lower opposed edges there are provided spaced mounting ears 31 and 32 formed by bending appropriate portions of the sheet metal at right angles to the plane of the part 26. To one side of the vertical center line of the jaw part 26, the sheet metal of the latter is extended at 33 at substantially right angles to the plane of the part 26, the extension 33 being slightly less than half the spacing between the apertured mounting ears 31 and 32. Thus the extension 33 is bent upwardly to provide a lever arm 34 which preferably makes an acute angle with the plane of the jaw part 26, and at its upper end the arm 34 is extended to the left as at 35, the latter extension being provided with a horizontal slot 36 open at one end as shown.

As above noted, the springy clamping element 28 is preferably mounted upon and carried by the clamping jaw plate and illustratively the latter may be provided with two clamping ears 37 punched out of its plane and engaging in open ended slots 38 in the lower side edges of the spring sheet metal of the element 28, whence the ears 37 are bent over to rigidly clamp the lower end portion of the springy clamping element 28 to the plate jaw 26. The upper end (as viewed in Fig. 6) of the clamping element 28 may thus move under its resiliency, toward or away from the main clamping jaw 26 and where the springy clamping element 28 is bent at its uppermost or jaw end to form a guiding lip 28^a as appears better in Fig. 4, the plate-like jaw 26 may have an elongated aperture 40 cut out of it so as to let the lip 28^a enter it if necessary.

The sub-assembly shown in Fig. 6 can thus be made up of two individual sheet metal elements each of which can readily and inexpensively be given its desired conformation by suitable stamping or other press operations. Two such sub-assemblies may now be interrelated, using the apertures in the interrelated space mounting ears 31 and 32 as aligning guides, and placing the two upstanding relatively rigid jaw elements 26 face to face, with the arm-like extensions 33 of each extending side by side and underneath and be-

yond the opposed plate-like jaw element, thus bringing the upstanding lever arm extensions 34 respectively to the two sides of the facing jaw elements. When so interrelated the pivoting ear 31 of the one unit is face to face with the pivoting ear 32 of the companion unit, and vice versa, and when so aligned the two clamping units or sub-assemblies are then related to the mounting ears 41 and 42, cut and bent out of a rectangular sheet metal mounting plate 43 (see Figure 5) and spaced apart to receive the assembled and inter-related spaced mounting ears of the two units therebetween. The mounting plate 43 is adapted to rest against the inside face of top wall 13 and has holes for the reception of securing screws 41. Ears 41 and 42 are also apertured and through the apertures of all the aligned mounting ears is then thrust a pivoting pin 44 (Figures 5 and 8), with a coiled spring 45 interposed between the spaced sets of ears and surrounding the pin 44. Pin 44 may then be upset or flattened at its ends as shown in Figure 8. The spring 45 has two ends 45^a and 45^b which are bent and are of lengths such that they extend through holes 34^a or rest against the horizontal extensions 33 and 33 of the two sub-assemblies, parts 33-33 extending side by side and underneath the pin 44 and the coil spring 45 as is better shown in Figure 8. The spring is so tensioned that it tends to unwind and its ends 45^a and 45^b, in pressing against the two axially spaced arm extensions 33 and 33, resiliently press these parts 33 downwardly (in Figure 6) in opposite directions, an action which holds the serrated jaw portions 30 of the two clamping jaws 26 and 27 tightly together but separable upon overcoming the action of the spring 45.

Were the resultant sub-assembly to be inserted through the open bottom end of the housing 12, the open-slotted horizontal lever extensions 35 would be brought alongside of the internal faces of the side walls 14 and 15 and since these horizontal extensions are of greater length than the width of the slots 20 and 21, they would transversely bridge these slots. However, before inserting the thus far assembled structure into the housing 12, the button-like actuators 22 and 23 are assembled to the structure; each of these actuators 22 and 23 is provided at its inner face with a headed stud 46 (see Figure 7) which if the parts 22 and 23 are made of moldable resin-like materials, may be in the form of a headed metal shank like a rivet and may have its shank anchored into the actuator during the molding of the latter. Accordingly actuator 22 (Fig. 3) with its headed stud 46 and actuator 23 with its headed stud 46 are now assembled to the two external and opposed lever arms 34 and 34 of the subassembly by simply sliding the stud shanks into the open ended slots 36 of the two horizontal extensions 35 (see Fig. 6).

The resultant sub-assembly comprising the parts shown in Fig. 5 and two sub-units such as that of Fig. 6, together with the two actuators 22 and 23, is now inserted into the housing 12 through its open bottom, to bring the flat mounting plate 43 against the under face of the top wall 13 as shown in Figs. 3, 4 and 8 whence it is secured thereto as by screws 47.

In so assembling the sub-assembly to the housing 12, the two sets of clamping jaws (see Fig. 4) are brought into appropriate alignment with the end wall slots 18 and 19, and the actuators 22 and 23 are, by the entering movement of the sub-assembly into the housing, brought into their

respective side wall slots 20 and 21 whose vertical edges (see Figs. 2 and 3) thereupon preclude such movement of the actuators relative to the slots 35 as would permit disengagement of the actuators from their respective lever arms 34 and 34. The assembly is thus completed.

Upon manually grasping the device as by applying the thumb to one actuator and the forefinger to the one on the opposite side (Figs. 1 and 4) and pressing the actuators inwardly of the side walls and hence towards each other, the action of the spring arms 45^a and 45^b may be overcome and the two jaw units are swung apart from each other, thus separating the jaw 26 from the jaw 27 (Fig. 4), that separating movement carrying with it an appropriate amount of separation of the spring-clamping elements 28 and 29 that are internally of and carried by the relative rigid jaws 26 and 27. Due to the relationship of the clamping units, with the operating lever of each passing underneath and to the other side of the other, the resultant movement toward each other of the two lever arms 34 and 34, as seen in Fig. 3, has a reverse action upon the clamping jaws and effects separation thereof.

A cable indicated at 48 in Fig. 9 and carrying a manually operable signal switch 49 at its end, as in a hospital bed installation, may now be entered into the open end wall slots 18 and 19, thus longitudinally traversing the inside space of the housing 12, and with the jaws open the cable thus enters in between the spring-clamping elements 28 and 29 (Fig. 4) which, according to the desired initial shaping and tensioning thereof, can yield away from each other to permit complete entry of the cable therein, the guiding lips 28^a and 29^a thereof being accommodated in the apertures 40 (Figs. 3 and 6) of the external clamping jaws. When completely entered into the spring-clamping elements 28 and 29, the latter by their spring action grip the cable and hold the cable and the entire device together as a unit even though the pressure on the actuators 22 and 23 is not yet released and hence even though the external jaws 26 and 27 are still held open.

In this latter condition any desired part to which the cable is to be attached may be brought into the open downwardly projecting jaws 26 and 27 and in Fig. 9 there is diagrammatically indicated at 50 a sheet or a blanket entered into the jaws 26 and 27 and securely held thereby, upon the release of the manual actuators 22 and 23. Should it be desired to loop a portion of the cable about some part such as a bed post or bed rail, in order thus to attach or position the signalling switch 49, the device and the cable are first attached to each other by the spring-clamping elements 28 and 29 as above described and having completed the loop, indicated at 50^a in Fig. 10, about the selected fixed part indicated at 51, the other portion 48^a of the loop is brought into the still open protruding jaws 26 and 27 by which it is gripped upon the release of the actuators, thus dependably insuring the maintenance of the loop and its action in securing the signalling switch 49 at the desired location.

The device is neat in appearance and is strong, reliable, and fool-proof in action or use. For example, in forcibly injecting or pressing the cable into the spring jaws 28 and 29, even after the cable reach 48 of Figures 9 and 10 has been passed through the rigid jaws 26 and 27, the guiding lips 28^a and 29^a are cammed away from each other by the pressure applied to the cable, wheth-

er or not such action is aided by keeping the finger pieces or actuators 22 and 23 pressed together so as to hold separated the jaws 26 and 27 and also the spring clamping elements 28 and 29; the guiding elements 28^a and 29^a are entered into the slots or apertures 40 of the external clamping jaws so as to give the spring clamping elements 28 and 29 a greater range of separating movement, and during such action the walls of the apertures 40 can guide and hold the respective spring elements against material distortion upwardly as viewed in Figure 4 under the applied pressure.

In Figures 11 and 12 I have shown a clamping device in which certain advantages of construction and action, over and above those above described with respect to the spring clamping elements 28 and 29, are achieved by making these spring clamping elements in one piece and by shaping them to achieve additional coactions with the above described slots or apertures 40 in the rigid clamping jaws. According to this modification of the invention, and in place of the two individual spring elements 28 and 29 of Figures 4, 6 and 8, I provide a single spring element 53 of flat spring stock, wide enough to be freely entered into the apertures 40 and of a length whereby it can be curved and shaped as is better shown in Figure 12 to provide it with a spring loop of a radius of curvature to be freely received between the parallel portions of the rigid jaws 26 and 27 when the latter are in closed position, the loop providing spring clamping elements 54 and 55 within and by which the cable is gripped and clamped. These elements 54 and 55 are extended downwardly and outwardly to provide relatively long guiding elements 54^a and 55^a which are furthermore extended so as to enter the apertures 40 in the two clamping jaws 26 and 27, terminating in end elements 54^b and 55^b which are bent at such an angle that, after being passed through the slots or apertures, they rest flatwise against the respective outer faces of the clamping jaws 26 and 27, thus to hold the spring unit 53 assembled to and in coacting relationship with the two jaws 26 and 27, the spring action of the part 53, in opposing opening up of the loop 54, acting also in a direction to bias the rigid jaws in closing or gripping direction.

With this construction, the lever elements or sub-units like that shown in Figure 6 and of which two are employed in making up each device, need not be provided with the clamping ears 37 or other means for fastening the spring elements thereto as in the embodiment of Figures 4 and 8, and thus the construction is simplified and improved, and with the embodiment of Figures 11 and 12 assembly is greatly facilitated, for the jaw parts 26 and 27 of the two lever units, in course of assembly, are simply snaked on to the bent ends of the spring unit 53 which becomes reliably interlocked therewith upon bringing the rigid clamping jaws into parallelism appropriate to aligning the holes in the pivoting ears 31 and 32 of the two lever ends for the reception of the pin 44.

In action, the device of Figures 11 and 12 may be used as illustratively described above in connection with Figures 9 and 10, the clamping force of the spring 45 being, if desired, materially supplemented or even supplanted, if desired, by the action of the spring loop of the spring unit 53 whose arms 54 and 55 can directly clamp the cable and through whose spring extensions 54^a and 55^a the relatively rigid clamping or gripping

actions on the part engaged therein or thereby.

The downward and outward curvature of the spring extensions 54^a and 55^a act as effective guides to enter the cable into the grip of the arms 54 and 55 of the loop, which are cammed apart by the camming action of the cable on the guiding parts 54^a and 55^a, and this action can be aided by holding the actuators 22 and 23 pressed toward each other, thus to separate the jaws 26 and 27 and by the bent-over end parts 54^b and 55^b cause the jaws to pull the two opposed spring arm portions of the spring unit 53 apart to aid in entering the cable into the spring loop; the parts, however, are preferably so proportioned that under these circumstances, that is with the jaws 26 and 27 in open position, the opposed spring arms are spaced apart by a distance less than the thickness of the cable. The spring arms thus yield under the pressure, forcing the cable into the loop, the apertures 40 permitting the extensions 54^a and 55^a to move in a direction respectively to the left and to the right relative to the jaws 26 and 27. Also with a cable already engaged and gripped in the spring loop, this relationship of the parts insures against release of the cable when the rigid jaw parts are manually separated, as when the sheet or other part 50 of Figure 9 is to be gripped by the jaws 26 and 27 or in case the latter are to be engaged over another cable reach such as the part 48^a of Figure 10. Throughout all of these actions the spring unit 53 remains dependably assembled to the relatively rigid jaws and the remaining parts of the device.

Where a spring 45 is employed as above described to coat in biasing the clamping elements, the arms 45^a and 45^b of the spring can in effect rest against the horizontal extensions 33 and 33 of the two lever ends or sub-assemblies, but to facilitate assembly of the latter to the mounting plate 43 (Figures 4, 5 and 12) it is preferred to provide each of the two arms 34 with holes 34^a closely adjacent to the extensions 33, to receive the respective ends 45^a and 45^b of the spring 45, as is best shown in Figures 4, 8 and 12. In this way also the spring arms can act to hold or position the spring during assembly for the passage therethrough of the pivoting pin 44 as above described, and also a longer and more facile lever-like action of these spring arms achieved.

It will thus be seen that there has been provided in this invention clamping devices for securing a flexible cable, in which the various objects above noted, together with many thoroughly practical advantages are successfully achieved. The device is fool-proof in operation and is safe, dependable and widely adaptable and flexible in action, and moreover makes it possible to dependably avoid the many deficiencies and the substantial damage inherent in the use of pins and safety pins as in heretofore known practices.

As many possible embodiments may be made of the above invention and as many changes might be made in the embodiment above set forth, it is to be understood that all matter hereinbefore set forth or shown in the accompanying drawing is to be interpreted as illustrative and not in a limiting sense.

I claim:

1. A clamping device for clamping a cable and for clamping another part comprising a housing open at its bottom and having open-ended slots in two opposed depending walls to receive a reach

of cable therein to thereby bridge the interior space in the housing, said housing having open-ended slots in two opposed depending walls to receive a finger piece member in each, a clamping unit receivable into the housing through its open bottom end and comprising two pairs of clamping elements of which one pair is of a length to extend beyond said open bottom end and the other pair is of a length to engage a reach of cable bridged through the housing in said first mentioned slots, two finger piece members for said clamping unit for actuating at least one pair of clamping elements and respectively enterable into said second mentioned slots upon entry of said clamping unit into said housing, and mechanical interconnections between said finger pieces and said clamping unit held against disconnection by entry of said finger pieces respectively into said second mentioned slots.

2. A construction as claimed in claim 1 in which said mechanical interconnections between each of said finger pieces and said clamping unit comprise a slot on one of the parts to be connected and a slot in the companion part to be connected, said headed part being entered into said part and said slot extending in a direction relative to the slot in which the finger piece is received so that the slot in which the finger piece is entered, in preventing movement of the finger piece, holds the headed member and its slot against movement of disassembly.

3. A construction as claimed in claim 1 in which said clamping unit has two opposed arms respectively juxtaposed to said second mentioned slots when the unit is entered into the housing, said mechanical connections of said finger pieces being respectively with said two opposed arms and comprising coacting parts interengageable upon relative movement therebetween in a direction other than the direction in which the finger piece is moveable relative to its housing slot upon assembly or disassembly of the clamping unit relative to the housing.

4. A clamping device for clamping a cable and for clamping another part comprising a housing open at its bottom end and having open-ended slots at two opposed sides thereof to receive a reach of cable therein to thereby bridge the interior space of the housing, said housing having a finger-piece-receiving cutout in a wall thereof, a clamping unit enterable into said housing through the open end thereof and comprising two pairs of clamping elements of which one pair extends beyond said bottom end for clamping a part beneath said housing and of which the other pair is of a length toward said open end to engage said bridging cable reach, said clamping unit having a finger piece for actuating at least one pair of clamping elements, said finger piece being entered, upon entry of said clamping unit into said housing, into said cutout of the housing.

5. A construction as claimed in claim 4 in which said clamping unit and said finger piece are provided with companion parts forming mechanical connecting means that are engageable or disengageable upon relative movement therebetween and being held against relative disengaging movement by the entry of said finger piece in said cutout.

6. A clamping device for clamping a cable and for clamping another part comprising a housing open at its bottom and having slots at two opposed ends to receive a reach of cable therein to thereby bridge the interior space in the housing and having open ended slots in its two op-

posed side walls for receiving finger pieces therein, a clamping unit enterable into said housing through its open bottom end and having means for securing it to the housing, said unit having two pairs of clamping elements of which one pair is of a length and extent to engage said bridging cable and the other pair is of a length to extend beyond said open bottom end to engage and clamp an extraneous part underneath said housing, said clamping unit having opposed finger pieces respectively entered into said opposed open-ended slots.

7. A construction as claimed in claim 6 in which the cable-clamping pair of clamping elements comprise spring-biased jaw elements respectively secured to the clamping elements of the other clamping pair and having terminal conformations to provide substantially an outwardly divergent mouth to facilitate entry of the cable reach thereinto.

8. A construction as claimed in claim 6 in which the cable-clamping pair of clamping elements comprise a loop-like member of spring material received between the clamping elements of the other clamping pair and having terminal extensions outwardly divergent to facilitate entry thereinto of said cable reach.

9. A construction as claimed in claim 6 in which the cable-clamping pair of clamping elements comprise a loop-like member of spring material received between the clamping elements of the other clamping pair and having terminal extensions outwardly divergent to facilitate entry thereinto of said cable reach, the clamping elements of said other pair having opposed cutouts and said terminal extensions having portions respectively entered into said cutouts.

10. A construction as claimed in claim 6 in which the cable-clamping pair of clamping elements comprise a loop-like member of spring material received between the clamping elements of the other clamping pair and having terminal extensions outwardly divergent to facilitate entry thereinto of said cable reach, the clamping elements of said other pair having opposed cutouts

and said terminal extensions having portions respectively entered into said cutouts.

11. A clamping device for clamping a cable and for clamping another part comprising two lever members each of substantially inverted U-shape with means pivotally connecting and spring-biasing them in a direction to bias their respective inner arms toward each other to effect clamping therebetween of a part and thereby bias their respective outside arms away from each other, and means forming cable engaging clamping jaws accommodated between said first mentioned two arms and being of shorter length than the latter, whereby pressing said outer arms toward each other to support said inner arms, the latter can engage and clamp a part other than said cable engaged by said first mentioned cable clamping means.

12. A construction as claimed in claim 11 in which said cable clamping means comprise two spring-biased members having means mounting them respectively to said two levers.

13. A construction as claimed in claim 11 in which said cable clamping means comprises two spring elements secured respectively to said two levers to partake of opening movement upon pressing said outside arms of the latter toward each other.

14. A clamping device as claimed in claim 11 in which said cable clamping means comprises a loop-like element of spring material received between said inner arms of said two levers and having terminal extensions respectively in mechanical interengagement with said inner arms of said two levers.

15. A clamping device as claimed in claim 11 in which said cable clamping means comprises a loop-like member of spring material having terminal extensions, said terminal extensions and said two inner arms of said two levers having lost motion connections.

LEO L. VERKUIL.
